UNITED STATES PATENT OFFICE

123,633

DESIGN FOR A FROST DISPELLER

Frank M. Woodward, Los Angeles, Calif.

Application September 13, 1939, Serial No. 87,193

Term of patent 3½ years

To all whom it may concern:

Be it known that I, Frank M. Woodward, a citizen of the United States, residing at Los Angeles, in the county of Los Angeles and State of California, have invented a new, original, and ornamental Design for Frost Dispellers, of which the following is a specification, reference being had to the accompanying drawing, forming part thereof.

The figure is a front perspective view of a frost dispeller, showing my new design.

The other side of the upper portion of the frost dispeller of my new design is substantially the same as that shown, while the rear end of the motor housing is plain, the other side thereof being the same as that illustrated.

I claim:

The ornamental design for a frost dispeller, as shown and described.

FRANK M. WOODWARD.
